America, a corporation of Delaware

Application January 22, 1947, Serial No. 723,624
In Great Britain January 25, 1946

10 Claims. (Cl. 28—32)

1

This invention relates to the winding of yarns and particularly to the beaming of yarns on warp beams with or without end flanges for supporting the ends of the yarn mass wound on the beam.

In the beaming of yarns it is sometimes the practice to reinforce the end portions of the yarn mass by the use of beaming collars, or strips of paper that are reinforced by the application along one edge of a strip of thicker material such as cardboard of a width less than the width of the paper. The paper is inserted between adjacent layers of yarn at intervals throughout the winding of the beam in such a way that the cardboard strip extends beyond the end portion of the yarn mass while the unreinforced part of the width of the paper is bound in by the adjacent layers of yarn as they are wound on the beam. The strips are inserted at such intervals that the thickness of yarn wound on the beam between the insertion of adjacent strips is equal to the thickness of the cardboard strip, so that the cardboard strips build up into a solid disc at the end of the yarn mass of a radius equal to that of the yarn mass. It has been found, however, that notwithstanding the added bulk of the thin paper that is included within the yarn mass, the ends of the yarn mass are apt to become sunken as compared with the main body of the mass. This is mainly due to the "shuffle" or slight traversing of the warp sheet to and fro along the length of the beam during winding, which is done to ensure the solidity and stability of the yarn mass wound on the beam.

In accordance with the present invention, a form of beaming collar in which this disadvantage is overcome and which possesses other advantages comprising a strip of thick pliant material such as cardboard faced on both sides with a thinner material such as paper, the thinner material on both sides projecting beyond one edge of the thicker material but to different distances. When a beaming collar of this construction is incorporated in the yarn mass during beaming in such a way that the thick material lies just outside the end of the yarn mass, the thinner material, which is included in the yarn mass, not only augments the bulkiness of the yarn at the end of the yarn mass to a greater extent than if a single layer were employed, but is also graduated in thickness by reason of the fact that one strip of thin material projects beyond the other. In this way the falling off of the density of yarn at the ends of the yarn mass is compensated for in a way that closely corresponds to the gradual way in which the density falls off.

2

By way of example, two forms of beaming collar according to the present invention and the method of making them will now be described in greater detail with reference to the accompanying drawings in which:

Figure 1 is a cross section of a beaming collar having a relatively wide cardboard strip therein,

Figure 2 is a view similar to Figure 1 of a collar having a narrower strip of cardboard therein and provided with a spaced fold so as to form a lip,

Figure 3 is a diagrammatic side elevation showing the method of forming the collars of Figures 1 and 2, and

Figure 4 is a diagrammatic section through a warp beam reinforced at its end with beaming collars in accordance with the invention.

Referring to Figure 1 the collars are formed in pairs, based on two strips 5 of cardboard, 1 in. in width, completely enveloped in a single continuous strip of paper 6, 7 ins. in width, the strips 5 being spaced apart by a distance of 2 ins., so that the edges of the paper 6 form two flaps 7 extending $\frac{1}{2}$ in. inside the inner edges of the strips. In the middle of the strip of paper 6, at 8, the paper is severed or almost severed completely through, so that the two halves of the pair of collars can be readily separated from one another for use. The separate collars thus have two flaps, one extending from each face of the cardboard strip therein, to a distance of $\frac{1}{2}$ and 1" respectively. The wider flap is pressed down at 9, at the inner edge of the strip 5, so as to lie in contact with the narrower flap 7.

The beaming collars shown in Figure 2 are similar to those in Figure 1, except that the strips of cardboard 10 are only $\frac{1}{4}$ in. in width and the paper 11 is only 5 ins. in total width. The strips 10 are separated by a distance of 3 ins. so as to leave a flap of $1\frac{1}{2}$ ins. extending beyond one face of the collar and $1\frac{1}{2}$ ins. beyond the other face of the collar. The wider flap is creased downwards as at 12 so as to lie in contact with the narrower flap 13. Round the outer edges of the strips 10 the fold 14 formed in the paper 11 is slightly spaced from the cardboard so that it can be crushed or pressed out of the plane of the cardboard to form a lip, as indicated on the right-hand side of Figure 2.

The collars shown in Figures 1 and 2 are formed in a roll, so that they are given a permanent curved set, which is of considerable assistance when applying them to the reinforcement of a beam. This is brought about during the production of the collars in the manner indicated in Figure 3. The strips of cardboard 5

are drawn from a roll 17, and are passed over and under rollers 18, by means of which they are caused to run through an adhesive in a vessel 19. On leaving the roll 18 the strips 5 pass to a roller 20, where they meet the paper 6 which is drawn from a roll 21, being guided to their proper position on the face of the paper by means of guides 22. On leaving the roller 20 the paper and cardboard together are passed through a folding guide 23, by means of which the paper projecting from each side of the strips 5 is folded over the strips towards the middle. The double strips 5 and 6 are then passed between forming rollers 24, 25, the upper roller 24 being a resilient roller, while the lower roller 25 is formed with a central enlarged portion 26 fitting into the space between the strips 5 and creasing the middle portion of the paper strip 6 round the inner edges of the cardboard strips 5 and into contact with the roller 24. A circumferential projection round the middle of the roller 25 cuts substantially through the paper so as to form a line along which the two halves can be readily separated. The product is then rolled up on a roll 27, on which it is allowed to remain until dry, so that the form given to it between the rollers 24, 25 and on the roller 27 is permanently set. When dry, the roll may be cut through along a radial line to form a set of double collars for use in winding a beam of appropriate size (i. e., one with external and internal diameters substantially equal to those of the finished roll as wound on the roller 27). It is not, however, essential that the previously fixed curvature of the collar should exactly match the curvature it will adopt in the wound beam. Accordingly, it may be more convenient to wind the assembled strips into a coil of larger diameter than the beams for which it is to be used, and to cut the collars from the coil in appropriate lengths when required.

The beaming collars according to the invention may be employed as the sole support for the ends of the yarn mass wound on the beam, the yarn mass being also reinforced by full-width beaming paper inserted at intervals between adjacent layers of yarn on the warp beam and extending across the full width of the warp. Indeed the invention contemplates the provision of a full-width beaming paper reinforced at both edges by strips of cardboard or like material, round the outer edges of which the edges of the paper are turned over so as to project inside the inner edges of the strip. The collars may also be employed, however, in conjunction with a beam flange and as separate collars without the use of the full-width beaming paper. In this case, by the provision of beaming collars having different widths of cardboard, the necessity for a fine adjustment of the position of the beam flange is obviated. Consequently, a beam whose flanges have only a coarse adjustment or no adjustment at all may be used, and the expense of providing for a fine adjustment is avoided.

The manner in which the beaming collars described above with reference to Figure 2 may be employed in beaming is shown in Figure 4, in which the yarn mass 30 is wound on a beam 31 and compressed between flanges 32. Between the end of the yarn mass 30 and the flange 32 are dispersed the strips 10, inserted at intervals during winding so that the paper flaps, are incorporated in the end of the yarn mass 30, the double flap entering into the extreme end of the yarn mass as at 33 while the single flap extends

further in as at 34. The collar is chosen as having a width of cardboard approximately sufficient to fill the space between the yarn mass 30 and the flange 32, the crushing of the lip 14 provides for some tolerance in this respect, and also prevents any stray turns of yarn lodged between adjacent beaming collars slipping between the collars and the flange 32.

Instead of using cardboard of 1 inch or $\frac{1}{4}$ inch in width other widths may be employed, for example a range consisting of 1 inch, $\frac{3}{4}$ -inch, $\frac{1}{2}$ -inch and $\frac{1}{4}$ -inch with a correspondingly narrower paper e. g. 7 inches, 6 inches, 5 inches and 4 inches so that, where a flanged beam is required a set of collars having strips of cardboard of the appropriate width can be selected.

Having described our invention, what we desire to secure by Letters Patent is:

- 20 1. A beaming collar comprising a strip of thick pliant sheet material faced on both sides with a thinner sheet material, the thinner material on both sides projecting beyond one edge of the thicker material in the same direction but to different distances.
- 25 2. A beaming collar comprising a strip of thick pliant sheet material faced on both sides with a single sheet of thinner material forming a fold round one edge of the thicker material and projecting beyond the other edge of the thicker material on both sides thereof in the same direction but to different distances.
- 30 3. A beaming collar comprising a strip of thick pliant sheet material faced on both sides with a single sheet of thinner material forming a fold round one edge of the thinner material, which fold is slightly spaced from said edge so that it can be pressed out of the plane of the thicker material to form a lip, said thinner material on both sides of the thicker material projecting beyond the other edge thereof but to different distances.
- 35 4. A beaming collar comprising a strip of thick pliant sheet material faced on both sides with a thinner sheet material, the thinner material on both sides projecting beyond one edge of the thicker material but to different distances, said collar having as a permanent set a curvature about an axis at right-angles to the length of said strip.

- 45 5. A beaming collar comprising a strip of thick pliant sheet material faced on both sides with a thinner sheet material, the thinner material on both sides projecting beyond one edge of the thicker material but to different distances and the thinner material on one side being pressed round said edge into contact therewith and with the thinner material on the other side of the thicker material, said collar having as a permanent set a curvature about an axis at right-angles to the length of said strip.
- 55 6. A beaming collar comprising a strip of thick pliant sheet material faced on both sides with a single sheet of thinner material forming a fold round one edge of the thicker material, which fold is slightly spaced from said edge so that it can be pressed out of the plane of the thicker material to form a lip, said thinner material on both sides of the thicker material projecting beyond the other edge thereof but to different distances, and the thinner material on one side being pressed round said edge into contact therewith and with the thinner material on the other side of the thicker material, said collar having as a permanent set a curvature about an axis at right-angles to the length of said strip.

- 65 7. A beaming collar comprising a strip of thick pliant sheet material faced on both sides with a single sheet of thinner material forming a fold round one edge of the thicker material, which fold is slightly spaced from said edge so that it can be pressed out of the plane of the thicker material to form a lip, said thinner material on both sides of the thicker material projecting beyond the other edge thereof but to different distances, and the thinner material on one side being pressed round said edge into contact therewith and with the thinner material on the other side of the thicker material, said collar having as a permanent set a curvature about an axis at right-angles to the length of said strip.

7. Beaming collars in the form of a pair of collars of opposite hand, each comprising a strip of thick pliant sheet material faced on both sides with a thinner sheet material, the thinner material on both sides projecting beyond one edge of the thicker material in the same direction but to different distances, the collars of the pair being united to one another at the edges of the thinner material which project further from the strips of thicker material.

8. A pair of beaming collars of opposite hand comprising a pair of spaced parallel strips of thick pliant sheet material faced on both sides with a single sheet of thinner material which is folded round the outer edge of each strip, and whose edges extend inwards beyond the inner edge of each strip but fall short of the centre line between said strips, said thinner material being substantially severed along said centre line so that the pair of collars are readily separable from one another.

9. A pair of beaming collars of opposite hand comprising a pair of spaced parallel strips of thick pliant sheet material faced on both sides with a single sheet of thinner material which is formed, round the outer edge of each strip, into a fold slightly spaced from said edge so that it can be pressed out of the plane of the thicker material to form a lip, and whose edges extend inwards beyond the inner edge of each strip but fall short of the centre line between said strips, said thinner material being substantially severed along said centre line so that the pair of collars are readily separable from one another.

10. A pair of beaming collars of opposite hand

35 Number 371,682

comprising a pair of spaced parallel strips of thick pliant sheet material faced on both sides with a single sheet of thinner material which is formed, round the outer edge of each strip, into a fold slightly spaced from said edge so that it can be pressed out of the plane of the thicker material to form a lip, and whose edges extend inwards beyond the inner edge of each strip but fall short of the centre line between said strips, 5 said thinner material being substantially severed along said centre line so that the pair of collars are readily separable from one another, the thinner material on one side of said strips being pressed round the inner edges of said strips into contact therewith and with the thinner material on the other side of said strips, said collars having as a permanent set a curvature about an axis at right-angles to the length of said strips.
